UNITED STATES PATENT OFFICE.

SIGMUND ADOLF ROSENTHAL, OF LONDON, ENGLAND.

BURNER.

SPECIFICATION forming part of Letters Patent No. 744,800, dated November 24, 1903.

Application filed January 10, 1902. Serial No. 89,205. (No model.)

To all whom it may concern:

Be it known that I, SIGMUND ADOLF ROSENTHAL, a citizen of Great Britain, residing at 37 Walbrook, in the city of London, England, have invented certain new and useful Improvements in and Relating to Burners, of which the following is a specification.

This invention relates to burners applicable for gas and vapor, and has for its object to provide a burner particularly for the purpose of a heating-stove, in which an intense heat may be produced by the perfect combustion of an intimate mixture of the gas or vapor and air.

According to the invention the mixing-chamber is formed of two hollow truncated cones having their apexes opposed so as to form an integral casing with a bore gradually restricted toward the middle, and at the top of the upper conical part of the casing to about one-third of its length an expansion-chamber is formed by the insertion of a closed cone provided in the manner and substantially as hereinafter described.

The invention further consists in the features of construction hereinafter described as applied.

The invention is illustrated in the accompanying drawings, in which—

Figure 1 is a sectional elevation of a stove provided according to the invention, while Fig. 2 is an elevation of a detail.

In carrying the invention into effect in the provision of a gas-stove a mixing-chamber is provided of two hollow truncated cones $a a$, having their apexes opposed and provided to form an integral casing having a bore gradually restricted toward the middle, the outwardly-flaring extremities a' and a'' thereby forming the top and bottom of the casing. The lower extremity a'' is secured to legs sufficiently high above the surface upon which the casing is made to stand as to permit of an adequate supply of air, or a ring c may be fitted within the cone a'' , to which ring c the legs b may be secured, the ring c being provided with suitable lateral apertures c' , through which free passage of air is allowed.

Beneath the mixing-chamber $a a$, and preferably secured to the supporting-legs b , an inlet gas-pipe e is provided whose nozzle e' projects upwardly and is disposed in such re-

lation to the mixing-chamber $a a$ as to insure an adequate supply, but not too great a supply of air for admixture with the gas supplied through the nozzle.

The upper conical part a of the mixing-chamber is to about one-third of its length transformed into a wide gas-expansion chamber f by the insertion of a closed cone g , made of metallic gauze—that is, having its base h and its conical periphery i formed of metallic gauze, the closed cone being inserted with its base h opposing the base of the upper conical part a of the mixing-chamber and its apex i' upward. The closed cone g rests against the wall of the mixing-chamber $a a$ and closes it. The metallic gauze of the closed cone is in the base part h , provided of a mesh finer than that of the conical peripheral part i .

The top part f of the expansion-chamber is provided with a circular sheet of metallic gauze k , preferably resting on the flange a^{11} of the cone and fastened in position by means of a ring n of angular section, which is held in position by means of bayonet-fastenings, the bayonet-slots being conveniently provided in the vertical flange of the ring n and the pins upon the face a^{12} of the cone. Any other suitable means for securing the gauze in position may, however, be employed. The ring is provided with short arms so shaped that a metallic deflecting-plate m can be placed and firmly held at a suitable distance above the flame, thereby deflecting and distributing the flame equally and at the same height between the top gauze and the plate.

The deflecting-plate m is preferably made in the form of a tray or pan, whose upper surface is of larger circumference than its under face, and it may have its periphery provided with vertical ribs, the recess m' of the plate being filled with a suitable material having for its object to obstruct the upward passage of the heat-rays in a vertical direction. A suitable material for this purpose is a mixture of infusorial earth and plaster-of-paris in the proportion of about one-quarter of the former to three-quarters of the latter; but any suitable refractory or non-conducting material may be advantageously used for the purpose.

By the provision of a stove, as hereinbefore

described, an intimate admixture of the air and gas or vapor is secured and perfect combustion in the flame.

What I claim as my invention, and desire 5 to secure by Letters Patent, is—

1. In a gas-stove, the combination of a mixing-tube gradually restricted in form toward the middle and flaring outwardly at its extremities, a gauze sheet at the top end thereof, 10 a closed cone of gauze inside and near the top of said tube, said parts forming an expansion-chamber, and a gas-nozzle, substantially as described.

2. In a gas-stove, the combination of a mixing-tube gradually restricted in form toward 15 the middle and flaring outwardly at its ex-

tremities, a gauze sheet at the top end thereof, a closed cone of gauze inside and near the top of said tube, said parts forming an expansion-chamber, a deflector-plate superposed upon 20 the top of said mixing-tube, said deflector-plate being formed of a hollow disk and filled with refractory material, and a gas-nozzle, substantially as described.

In testimony whereof I have signed my 25 name to this specification in the presence of two subscribing witnesses.

SIGMUND ADOLF ROSENTHAL.
